UNITED STATES PATENT OFFICE.

CLYDE D. LOVE, OF COSHOCOTON, OHIO.

SUNDIAL.

1,396,937.

Specification of Letters Patent.

Patented Nov. 15, 1921.

Application filed October 27, 1920. Serial No. 420,025.

To all whom it may concern:

Be it known that I, CLYDE D. LOVE, a citizen of the United States, residing at Coshocton, in the county of Coshocton and State of Ohio, have invented certain new and useful Improvements in Sundials, of which the following is a specification.

The present invention relates to certain new and useful improvements in sun dials, 10 and has for its object to provide a device of this character which embodies novel features of construction whereby it can be readily adjusted for different longitudes to compensate for the equation of time and give a reading 15 in standard time instead of sun time.

Further objects of the invention are to provide a device of this character which is comparatively simple and inexpensive in its construction, which can be easily and quickly 20 adjusted and locked or released from the front of the dial without the necessity of reaching around to the back thereof, and which is susceptible of being made in embodiments adapted for use for advertising purposes. 25

With these and other objects in view the invention consists in certain combinations, arrangements, and associations of the parts, as will more fully appear as the description 30 proceeds, the novel features thereof being pointed out in the appended claims.

For a full understanding of the invention reference is to be had to the following description and accompanying drawings, in 35 which:

Figure 1 is a front elevation of a sundial which is constructed in accordance with the invention;

Fig. 2 is a vertical sectional view through 40 the same on the line 2—2 of Fig. 1;

Fig. 3 is a detail view of the lower end of the gnomon;

Fig. 4 is a rear elevation of the sun dial;

Fig. 5 is a vertical sectional view through 45 a modified form of the sun dial; and

Fig. 6 is a detail view of the adjustable mounting for the dial in the said modified form.

Corresponding and like parts are referred 50 to in the following description and indicated in all of the views of the drawings by like reference characters.

The sun dial may obviously be constructed for mounting in either a vertical, horizontal 55 or angular position, although for illustrative purposes two embodiments of the inven-

tion are shown which are vertically disposed. In the preferred form of the invention, illustrated by Figs. 1 to 4 inclusive, the numeral 1 designates the base and 2 the dial which is carried by the base and adjustably mounted in a spaced relation thereto. The base 1 preferably has an elongated formation, being provided at its extremities with openings 3 arranged to receive screws or other fastening members for securing the base to a vertical support, which support should face due south. The dial 2 may be conveniently formed of some light material such as sheet metal, and is illustrated as being 60 circular in shape and surrounded by a peripheral flange 4 which is bent rearwardly from the edges thereof. A stiffening plate 5 is shown as secured to the back of the dial 2 at substantially the central portion thereof, and an angularly shaped bracket 6 is secured to the reinforced portion of the dial. A complementary bracket 7 is secured to the base 1 and the outstanding wings 6^a and 7^a 65 of the respective brackets are pivotally connected by a bolt 8. Each of the angularly formed brackets 6 and 7 is shown as constructed with a reinforcing web 9.

The gnomon 10 is in the form of a substantially triangular plate which projects from 85 the dial 2 at right angles to the face thereof. The shadow casting edge 10^a of the gnomon is at the proper angle so that it will be parallel to the axis of the earth when the sun dial is set up in operative position. The 90 pivot bolt 8 which forms the axis about which the dial is turned while adjusting the same is exactly parallel to the shadow casting edge 10^a of the gnomon, and the bearing faces of the outstanding wings 6^a and 7^a 95 of the brackets 6 and 7 are arranged at right angles to the said bolt 8 and shadow casting edge of the gnomon.

The gnomon is detachably secured to the dial, being constructed at the inner end 100 thereof with a lateral flange 11 which fits securely against the face of the dial and is formed with a positioning stud 12 and an opening 13. This stud 12 is adapted to pass through corresponding openings in the dial 105 2 and stiffening plate 5, and the opening 13 is adapted to register with other openings in the dial and stiffening plate and to receive one of the fastening members or bolts 14 by means of which the stiffening plate is secured to the dial. The gnomon is thus accurately and rigidly secured in place upon the 110

dial by the use of only a single fastening member, and this is a feature which is an advantage when knocking down and packing the sun dials for shipment, as well as when 5 assembling them in the shop or field.

The face of the dial 2 is provided with the usual hour scale 15 which is graduated and marked in the proper manner for coöperation with the shadow cast by the gnomon 10 to indicate the time either in the morning or in the afternoon. If desired, the face of the dial may also carry suitable advertising matter such as that indicated at 16. The sun dial is mounted in position so as to face 15 due south. The gnomon must then be in the plane of the meridian and the shadow casting edge 10^a thereof must be at such an angle that it is exactly parallel with the axis of the earth. In this position the sun 20 dial will indicate sun time clearly, although an adjustment is necessary for the different longitudes in order that the readings of the sun dial may be in standard time instead of sun time. The adjustment must be made, 25 however, without destroying the parallel relation between the shadow casting edge of the gnomon and the axis of the earth. It is accordingly important that the axis upon which the dial is turned shall be parallel or coincide with the shadow casting edge of 30 the gnomon. In the construction illustrated by Figs. 1 to 4 of the drawings the pivot bolt 8 is parallel to the shadow casting edge of the gnomon while the bearing faces of the 35 brackets 6 and 7 are at right angles thereto. The dial can thus be turned upon the pivot bolt and properly positioned to compensate for time without interfering with the proper adjustment or mounting of the gnomon.

40 The pivot bolt 8 is preferably of such a length as to extend forwardly through the front of the dial 2, and a sleeve 17 which is fitted upon the bolt is interposed between the bracket 7 and a wing nut 18. This 45 wing nut is arranged in front of the dial 2 and provides a means for easily releasing the bolt or tightening the same preparatory to or after making an adjustment.

A possible modification is illustrated by 50 Figs. 5 and 6 in which the base 1^a has a tongue 19 stamped therefrom and bent upwardly to provide one of the pivot brackets. In a similar manner the dial 2^a has a tongue 20 stamped therefrom and bent rearwardly 55 to form the other bracket. The pivot bolt 21 extends through the brackets 19 and 20 and is provided with a clamping nut 22 which partially projects through the opening in the dial from which the tongue 20 60 was cut, thereby enabling the nut to be readily manipulated from the front of the dial. This pivot bolt 21 has a tubular formation and is interiorly threaded to receive the inner end of the gnomon 23, said gnomon 65 being in the form of a rod. This gno-

mon must, of course, project in such an angle that it is parallel to the axis of the earth, and it will be obvious that when the clamping nut 22 is loosened the dial can be turned upon the pivot bolt to adjust the same in 70 the manner previously indicated. This is a simple construction which can be inexpensively manufactured, although the results are substantially the same as those which are obtained with the other construction. 75

While only two forms of the invention have been shown and described for illustrative purposes, it will be obvious that many modifications and changes can be made in the details of construction without departing from the spirit or scope of the invention. 80

Having thus described my invention, what I claim as new and desire to secure by Letters Patent, is:—

85 1. A sun dial including a gnomon, a substantially flat dial associated therewith, and a pivot bolt upon which the dial is adjustably mounted, the axis of the pivot bolt being parallel to the shadow casting edge of 90 the gnomon.

2. A sun dial including a gnomon, a dial associated therewith and pivotally mounted to swing upon an axis having the same direction as the shadow casting edge of the gnomon, and clamping means for holding the dial in an adjusted position, said clamping means being arranged to be manipulated from the front of the dial. 95

3. A sun dial including a gnomon, a dial associated therewith, a support arranged back of the dial and upon which the dial is pivotally mounted to turn about an axis parallel to the shadow casting edge of the gnomon, and clamping means adjustable 100 from the front of the dial for holding the dial in an adjusted position. 105

4. A sun dial including a base, a dial, a gnomon associated with the dial, complementary pivot ears projecting from the dial and base, and a pivot bolt connected to the pivot ears, the bolt being parallel to the shadow casting edge of the gnomon while the bearing faces of the pivot ears are arranged at right angles thereto. 115

5. A sun dial including a base, a dial having an opening in the face thereof, a gnomon associated with the dial, complementary pivot ears projecting from the dial and base, a pivot bolt connecting the pivot ears and arranged parallel to the shadow casting edge of the gnomon, and a clamping nut upon the bolt for holding the dial in an adjusted position, said clamping nut projecting through the before-mentioned opening in the 120 face of the dial so as to be accessible from the front thereof. 125

6. A sun dial including a base, a dial having an opening in the face thereof, a gnomon associated with the dial, complementary pivot 130

ears projecting from the base and dial, a pivot bolt connecting the ears and arranged parallel to the shadow casting edge of the gnomon, said pivot bolt extending through 5 the before-mentioned opening in the face of the dial, a clamping nut applied to the bolt, and a sleeve interposed between the clamping nut and the pivot ears.

7. A sun dial including a dial plate having 10 openings in the face thereof, a gnomon provided at the base thereof with a flange

adapted to fit against the dial, said flange being provided with a positioning pin and an opening and the positioning pin being adapted to engage one of the openings of the 15 dial plate while the opening is adapted to register with another opening of the dial plate, and a detachable fastening member extending through the registering openings.

In testimony whereof I affix my signature. 20

CLYDE D. LOVE.
